UNITED STATES PATENT OFFICE.

WALTER L. SIEWERS, OF WINSTON-SALEM, NORTH CAROLINA.

DESIGN FOR AN UNDERGARMENT.

43,784.

Specification for Design.

Patented Apr. 1, 1913.

Application filed December 7, 1912. Serial No. 735,534. Term of patent 14 years.

To all whom it may concern:

Be it known that I, WALTER L. SIEWERS, a citizen of the United States, residing at Winston-Salem, in the county of Forsyth and State of North Carolina, have invented a new, original, and ornamental Design for an Undergarment, of which the following is a specification, reference being had to the accompanying drawing, forming a part thereof.

The drawing is a perspective view of the garment seen from the front.

The garment shown in the accompanying drawing is composed of a tubular knit fabric 1 having the wales of the knitting running longitudinally of the garment being cut from opposite sides as at 2 upon the curves as shown with a central V-shaped cut 3 and a back cut 4, the V-shaped cut 3 being lower

in its lowest limit than the cut 4 and also lower than the cuts 2 from the sides, while the cut 4 is higher than either the cuts 2 or 3. The several cut portions are finished by an ornamental beading or trimming 5 with the beading from the cuts 3 and 4 connected directly along their side edges with the beading from the cuts 2 as indicated at 6, such binding, beading or trimming secured together forming the shoulder straps upon the curves and in the ornamental manner shown.

I claim—

The ornamental design for an undergarment as shown and described.

WALTER L. SIEWERS.
